[57] CLAIM

The ornamental design for a boat stabilizer, as shown and
described.

DESCRIPTION

FIG. 1 is a top perspective view of a boat stabilizer showing
my new design;

FIG. 2 is a bottom perspective view thereof;

FIG. 3 is a top plan view thereof;

FIG. 4 is a rear elevational view thereof;

FIG. 5 is a bottom plan view thereof; and,

FIG. 6 is a side elevational view thereof, the opposite side
elevational view being a mirror image of that shown.
